UNITED STATES PATENT OFFICE.

JAMES WARES BRYCE, OF BLOOMFIELD, NEW JERSEY, ASSIGNOR TO THE AEOLIAN COMPANY, A CORPORATION OF CONNECTICUT.

EXPRESSION-DEVICE CONTROL.

1,278,845.

Specification of Letters Patent. Patented Sept. 17, 1918.

Application filed December 22, 1916. Serial No. 138,465.

To all whom it may concern:

Be it known that I, JAMES WARES BRYCE, a citizen of the United States of America, and a resident of Bloomfield, Essex county, 5 and State of New Jersey, have invented certain new and useful Improvements in Expression-Device Controls, of which the following is a specification, reference being had to the accompanying drawings, forming a 10 part thereof.

My invention relates to improvements in remote control for expression devices for musical instruments and more specifically for electrically actuated means for controlling the expression devices for phonographs such, for example, as a valve for varying the 15 volume of sound produced by such an instrument.

Its object is to provide a simple, efficient 20 and sensitive electro-responsive actuating mechanism for expression devices with a manually operable graduated current control device, by means of which a person at any desired distance from a musical instrument may control such an expression device, 25 at will.

In order that my invention may be thoroughly understood I will now proceed to describe the same in the following specification and then point out the novel features 30 thereof in appended claims.

Referring to the drawings:

Figure 1 is a side elevation, partly in section, of certain parts of a phonograph or 35 the like, with actuating and control devices embodying my invention applied thereto, the latter being shown diagrammatically.

Fig. 2 is a diagrammatic representation of 40 a modified form of sensitive relay and which forms a part of this invention.

Fig. 3 is a diagram showing certain modifications in the arrangement of circuits which may be employed under certain 45 circumstances.

Like characters of reference designate corresponding parts in all the figures.

10 designates the tone arm of the instrument to be controlled, and 11 a part of its 50 sound chamber; 12 is the expression device, in this case a valve arranged to be moved by a rod 13 toward or away from its seat, to thereby produce more or less restriction to the size of the sound passage, and to thereby

vary the volume of sound emitted from the 55 instrument.

14 is the speed governor of the instrument and 15 the friction disk of the governor.

The electro-responsive motor is designated generally by the reference numeral 20. In 60 the specific embodiment of the invention illustrated, this motor comprises a pair of similar solenoids 21—22, a common core 23, and a dash pot 24 connected with the core. 25 is a bell crank lever pivoted at 26 with one of its arms connected with the core 23 by a link 27 and its other arm connected with the valve rod 13 by means of a rod 28 and another bell crank lever 29.

30 is a rod extending rigidly from the bell 70 crank lever 25 and carrying a weight 31 by means of which the bell crank lever and the different elements which are connected therewith, may be counterbalanced to a desired extent.

32 is another arm rigidly connected with but insulated from the bell crank lever 25. This carries at its outer end an electrical contact 33 which is adapted to slide over and make electrical connection with various 80 points on a rheostat 34 as the positions of the bell crank lever 25 and of the valve 12 are changed.

40 is a manually operable current varying 85 or control device which comprises a rheostat 41 similar in resistance to the rheostat 34, a movable contact 42 and an actuating thumb or finger piece 43.

A sensitive relay is interposed between this manual control device and the electro-responsive motor 20. This is designated by 90 50 and comprises an electro-magnet 51 which has two spaced poles 52—53 and two magnet windings 54—55 wound in opposite directions. An arm 56 pivoted at 57 carries a polarized armature 58. This is held by a spring 59 in a position midway between the magnet poles 52—53 when the latter are not magnetized.

60 is an electric generator which represents a suitable source of electric current supply. 61 is a lead from this generator, and 62 a resistance connected therewith. A wire 63 connects this resistance with the magnet winding 54, the other end of which 100 is connected by a wire 64 with one end of the rheostat 34. Another wire 65 connects resistance 62 with magnet winding 55, the 105

other end of which is connected by a wire 66 with the end of rheostat 41. A wire 67 is connected with the contact member 42. A branch 68 of this wire leads to the contact 5 carrying arm 32 and another branch 69 leads to the other side of the generator 60.

In the circuits 66-67, a plug 70 is interposed. 70^a designates another plug which may be conveniently located in another place 10 with which the manual control device may be connected.

71 is a switch by means of which the circuit hereinbefore pointed out may be opened or closed manually. This is interposed in 15 the wire 69. An automatic switch 72 is also interposed in the wire 69. This comprises an arm 73 carrying a contact at its outer end and a similar arm 74 connected with but insulated from the arm 73. These two arms 20 are of spring metal and are so arranged that when free to assume their natural positions, will close between them the contacts which they carry, thereby carrying any current which may be passing through the wire 69. 25 The arm 74 however, is of sufficient length to extend into the path of travel of the speed governor contact plate 15 and the parts are so proportioned and arranged that when the speed governor 14 is at rest its friction disk 30 will engage this arm 74 and separate its contact from that carried by the arm 73, thus opening the circuit. It is evident however, that when the speed governor is rotated, its friction disk 15 will be removed from arm 74 35 and that this will allow the contacts on the arms 74 and 73 to come together.

On the upper end of the pivoted arm 56 is a contact 80 which is arranged to be moved from side to side against one or the 40 other of two stationary contacts 81 or 82. A wire 83 is led from the stationary contact 81 to the winding of solenoid 22. 84 is another wire from contact 82 to the winding of solenoid 21. The other ends of these 45 solenoid windings are connected together by a wire 85 from which a wire 86 runs to the generator 60. The other end of the generator is connected by a wire 87 with the pivoted arm 56 and its contact 80.

50 Before describing the devices shown in the other figures of the drawing, I will describe the operation of this device. When the manual control device 40 is in the position shown, the sensitive relay 50, the motor 55 20 and the valve 12 will be in the positions in which they are shown. Now, when the phonograph motor (not shown) is started the speed governor 14 will be actuated and this, as has been pointed out, will cause 60 the contacts on arms 73-74 to be brought together so that if the switch 71 is closed two circuits will thereby be closed from the generator 60 through the windings of the sensitive relay 50. These may be traced as 65 follows:—first from the generator 60 through

resistance 62, through winding 55, wire 66, contact 42, wires 67 and 69 to generator. Second, from generator 60, through resistance 62, wire 63, winding 54, wire 64, contact 33, contact arm 32, and wires 68-69 to the other side of the generator.

The current through these two circuits will be equal and as the number of convolutions in the magnet windings 54-55 are equal and opposite, these currents will have 75 no effect whatever upon the magnet 51 and the pivoted arm 56 will remain in its central position.

Now, if the manual control device is moved along on rheostat 41, the first effect 80 of this will be to insert a part of the resistance of this rheostat in the circuit through magnet winding 55. This will immediately throw the magnet 51 out of magnetic balance and will cause the polarized armature 85 58 to be drawn to one side, in this case to the right. The circuit will thereby be closed to the solenoid winding 21 which circuit may be traced as follows:—from generator 60 to wire 87, pivoted arm 56, contacts 80-82 90 and wire 84 to the solenoid winding 21; thence through wires 85-86 to the other side of the generator. This will of course cause the core 23 to be moved upward. This upward movement will, through the 95 mechanical connections previously described, move the valve 12 upward toward its seat to thereby restrict the size of the passage which it controls in the sound chamber.

100

The movement of the solenoid 23 and its connected parts will continue until the movable contact 33 reaches a position on rheostat 34 which corresponds with the position which the contact 42 now has on rheostat 105 41. This will reduce the current in magnet winding 54 to the same extent that the current in magnet winding 55 has been reduced and will thereby reestablish the magnetic effect of the magnet windings 54 and 110 55 and allow the pivoted arm 56 to again assume its central position under the influence of spring 59, thereby moving the contact 80 away from contact 82 and breaking the circuit through solenoid winding 21 115 so that the core 23 and the parts mechanically connected therewith will come to rest.

A further movement of contact 42 on rheostat 41 in the same direction will 120 similarly cause a further upward movement of the valve 12.

If the contact 42 is moved back toward its initial position this will immediately cause an increase of current in the magnet 125 winding 55 which will cause the polarized armature 58, pivoted arm 56 and contact 80 to be moved to the left; in this case closing a circuit from the generator through contacts 80-81, wire 83, to and through 130

solenoid winding 22, thence through wires 85 and 86 back to the generator. In this manner the core 23 will be moved downward and this downward movement will be imparted to the valve 12 until the contact arm 33 reaches a position on rheostat 34 corresponding with the new position of contact 42 on rheostat 41. This will, as in the former case, reestablish the balance between the magnetic effects of the magnet windings 54—55 and allow the pivoted arm 56 under the action of spring 59 to again assume its central position, thus breaking the circuit between contacts 80 and 81.

15 The dash pot 24, when used, prevents any sudden or jerking movement of the electro-responsive motor 20.

Referring now to Fig. 2, the form of sensitive relay there shown, comprises two electro-magnets 51^a and 51^b. Each of these has a polarized armature 58^a and 58^b on pivoted arms which are held away from their respective magnet poles by means of suitable springs. Each of these magnets also comprises windings 54^a and 55^a, 54^b and 55^b, those of each magnet being equal in number of convolutions and wound in opposite directions.

Without specifically tracing the circuits 30 it may be seen that when the magnetic effect of currents passing through windings 54^a, 55^a, 54^b, 55^b is thrown out of balance, by means of manual adjustment of the control device 40, one of these magnets will 35 cause its armature to be drawn toward its pole piece and the other will have a tendency to repel its armature on account of the fact that these polarized armatures are polarized in opposite directions. On account of this fact either one or the other 40 of the magnets 51^a, 51^b will close a circuit at 81^a or 82^a whenever the current flowing through the magnet windings is thrown out of balance and this will in the other case, 45 cause either solenoid winding 21 or solenoid 22 to be energized to thereby move the valve 12 an amount and in a direction corresponding with the amount and direction of movement of the contact 42 of the manual control device over rheostat 41.

Referring now to Fig. 3, the parts therein correspond with the parts shown in Fig. 1, with the exception that in this case the generator 60^a is an alternating current generator and that in this case a battery 60^b is used for the current supply for the magnet windings 54—55 and the circuits therefor including the manual control device 40 and the rheostats 41 and 34. The operation of this 55 form of the sensitive relay and its connected parts is similar to that previously described in connection with Fig. 1, with the exception that in this case the solenoid windings 21 and 22 are energized by alternating current from the generator 60^a and that the

core 23 in accordance with the usual practice should be laminated to work effectively with currents of this character.

Such expression control valves as 12, as have heretofore been used, have been actuated by means of mechanical devices operable either at the instrument or within a short distance from the instrument.

There is practically no limit to the distance from the instrument which the operator may desire to assume. I have shown plugs such as 70 and 70^a for the purpose of illustrating the fact that several such plugs may be provided at places located at different distances from the instrument to which the manual control device 40 may be attached, so that the operator may be able to control the instrument from different desired locations.

Another advantage of this arrangement is 85 that but two wires are required to connect the remote manual control device with the other parts of the apparatus, all of which may be installed within the sound producing instrument itself. It is my intention to have 90 the wires between the manual control device and the plug flexible so that the operator will be able to move freely the hand in which it is held.

The invention is shown as applied to a 95 talking machine or phonograph, but I do not intend to limit myself to this specific case. I have illustrated several modifications of certain parts of the apparatus to show that I do not limit myself to any 100 specific form or construction, and in fact intend no limitations other than those imposed by the appended claims.

What I claim is:

1. An expression control device for musical 105 instruments comprising a movable member, a motor arranged to actuate said member different desired amounts in opposite directions, and a remote control device connected with said motor whereby said motor may be 110 made to actuate the member to an amount and in a direction desired.

2. An expression control device for musical 115 instruments comprising a movable member, a motor arranged to actuate said member different desired amounts in opposite directions, and a remote control device electrically connected with said motor whereby said motor may be made to actuate the member.

3. An expression control device for musical 120 instruments comprising a movable member, an electric motor connected to actuate said member different desired amounts and in opposite directions, and a remote manual control device connected with said motor.

4. An expression control device for musical 125 instruments comprising a movable member, an electric motor connected to actuate said member, a remote manual control device for the motor, a sensitive relay balanced mag-

- netically between the motor and control device, and means actuated by the manual control device and by the motor for disturbing and restoring the magnetic balance of the 5 relay.
5. An expression control device for musical instruments comprising a movable member, an electric motor connected to actuate said member, a remote manual control device for 10 the motor comprising an adjustable current varying element, a sensitive relay having opposed magnet windings and motor control contacts; and a motor controlled adjustable current varying element, said manually controlled 15 current varying element being in one of the relay magnet windings and the motor controlled current varying element being in the other relay magnet winding.
6. An expression control device for musical 20 instruments comprising a movable member, an electric motor connected to actuate said member, a remote manual control device for the motor comprising an adjustable rheostat, a sensitive relay having magnet windings arranged to carry currents in opposite directions, and motor control contacts; and a motor controlled adjustable rheostat, said 25 manually controlled rheostat being in one of the relay magnet windings and the motor controlled rheostat being in the other relay magnet winding.
7. An expression control device for musical 30 instruments comprising a movable member, an electric motor connected to actuate said member, a remote manual control device for the motor, a sensitive relay between the motor and the manual control device, said relay comprising a pair of pole pieces, a polarized armature and motor circuit closers controlled thereby, yielding means for holding said armature away from the pole pieces and the motor circuit closers open, opposed balanced means for magnetizing 35 said pole pieces, and means actuated by the manual control device and by the motor for disturbing and restoring the magnetic balance of the relay to close and open said motor circuit closers.
8. An expression device for musical 40 instruments comprising a movable member, an electric motor connected to actuate said member, a remote manual control device for the motor comprising an adjustable rheostat, a sensitive relay having magnet windings arranged to carry currents in opposite directions, a pair of opposed pole pieces, a polarized armature and motor circuit closers controlled thereby, and yielding means for holding said armature between and away 45 from said pole pieces and said motor circuit closers open; and a motor controlled adjustable rheostat, said manually controlled rheostat being in one of the relay magnet windings and the motor controlled rheostat 50 being in the other relay magnet winding.
9. An expression control device for musical instruments comprising a movable member, a pair of solenoids connected to actuate said member, circuits for said solenoids, a remote manual control device for said solenoid 55 circuits comprising an adjustable rheostat, a sensitive relay having magnet windings arranged to carry currents in opposite directions, a pair of opposed pole pieces, a polarized armature and motor circuit closers in the respective solenoid circuits controlled thereby, and yielding means for holding said armature between and away from said pole pieces and said motor circuit closers open; and an adjustable rheostat controlled by said 60 solenoids, said manually controlled rheostat being in one of the relay magnet windings and the solenoid controlled rheostat being in the other relay magnet winding.
10. An expression control device for musical 65 instruments comprising a movable member, an electric motor connected to actuate said member different desired amounts and in opposite directions, a remote manual control device electrically connected with said 70 motor, and a two-wire circuit for said control device.
11. An expression control device for musical 75 instruments comprising a movable member, an electric motor connected to actuate said member, a remote manual control device for the motor, a sensitive relay balanced magnetically between the motor and control device, means actuated by the manual control device and by the motor for disturbing and restoring the magnetic balance of the relay, a two-wire circuit from said relay comprising a plurality of connecting sockets, a connecting plug adapted to fit said sockets, and a pair of flexible wires 80 between the manual control device and said plug.
12. An expression control device for a phonograph having a driving motor and a sound passage comprising a movable valve 85 in said sound passage, an electric motor connected to actuate said valve different desired amounts and in opposite directions, a remote manual control device electrically connected with said motor, a two-wire circuit for said control device, and an automatic switch in said circuit arranged to be actuated by said driving motor.
13. An expression control device for a phonograph having a driving motor and a 90 sound passage, comprising a removable valve in said sound passage, a pair of aligned solenoids, circuits therefor, a common core for said solenoids, a dash pot connected with said core, mechanical connections between 95 the solenoid core and the movable valve, a remote manual control device for the motor comprising an adjustable rheostat, a sensitive relay having magnet windings arranged to carry currents in opposite directions, a 100
- 105
- 110
- 115
- 120
- 125
- 130

pair of opposed pole pieces, a polarized armature and motor circuit closers controlled thereby, and yielding means for holding said armature between and away from said pole pieces and said motor circuit closers open; and a motor controlled adjustable rheostat, said manually controlled rheostat being in one of the relay magnet windings and the motor controlled rheostat being in the other

relay magnet winding, and a two-wire circuit from said relay comprising a plurality of connecting sockets, a connecting plug adapted to fit said sockets; and a pair of flexible wires between the manual control device and said plug. 10

In witness whereof, I have hereunto set my hand this 20th day of December, 1916.

JAMES WARES BRYCE. 15

Copies of this patent may be obtained for five cents each, by addressing the "Commissioner of Patents, Washington, D. C."

It is hereby certified that in Letters Patent No. 1,278,845, granted September 17, 1918, upon the application of James Wares Bryce, of Bloomfield, New Jersey, for an improvement in "Expression-Device Controls," errors appear in the printed specification requiring correction as follows: Page 3, line 98, for the word "ease" read use; page 4, line 121, claim 13, for the word "removable" read *movable*; and that the said Letters Patent should be read with these corrections therein that the same may conform to the record of the case in the Patent Office.

Signed and sealed this 22d day of October, A. D., 1918.

[SEAL.]

R. F. WHITEHEAD,

Acting Commissioner of Patents.

Cl. 274—1.
